UNITED STATES PATENT OFFICE.

ROWLAND H. MAXFIELD, OF KINGS VALLEY, OREGON.

VEHICLE-BRAKE.

1,081,850.

Specification of Letters Patent.

Patented Dec. 16, 1913.

Application filed February 19, 1913. Serial No. 749,471.

To all whom it may concern:

Be it known that I, ROWLAND H. MAXFIELD, a citizen of the United States, residing at Kings Valley, in the county of Benton and State of Oregon, have invented new and useful Improvements in Vehicle-Brakes, of which the following is a specification.

This invention relates to vehicle brakes, and it has particular reference to that class 10 of brakes which are known as automatic or self-acting.

One object of the invention is to produce an automatic brake of simple and efficient construction which may be readily applied 15 to and used in connection with the running gear of an ordinary wagon.

A further object of the invention is to produce a simple and efficient construction in inactive position so as to enable the vehicle to be backed by the means ordinarily provided for the purpose.

A further object of the invention is to simplify and improve the general construction of the device including the actuating means and the support and housing for the same.

With these and other ends in view which will readily appear as the nature of the invention is better understood, the same consists in the improved construction and novel arrangement and combination of parts which will be hereinafter fully described and particularly pointed out in the claims.

In the accompanying drawings has been
35 illustrated a simple and preferred form of
the invention, it being, however, understood
that no limitation is necessarily made to the
precise structural details therein exhibited,
but that changes, alterations and modifica-
40 tions within the scope of the claims may be
resorted to when desired.

In the drawings,—Figure 1 is a top plan view of a running gear equipped with the improved brake. Fig. 2 is a longitudinal vertical sectional view of the same. Fig. 3 is a vertical sectional view, enlarged, taken on the line 3—3 in Fig. 1. Fig. 4 is a horizontal sectional view taken on the line 4—4 in Fig. 3. Fig. 5 is a transverse sectional view taken on the line 5—5 in Fig. 3. Fig. 6 is a perspective detail view of the supporting frame detached.

Corresponding parts in the several figures are denoted by like characters of reference.

55 For purposes of illustration a conventional running gear has been shown includ-

ing front and rear axles 10, 11, a hound frame 12 with which the tongue 13 is connected by a transverse pivotal rod 14, a reach bar 15 supporting a cross bar 16 and rear hounds 17. The tongue is provided with a longitudinal slot 18 about which is mounted a frame comprising a longitudinal guide member 19 having legs or supports 20 which are fastened on the tongue by means of bolts 21, the longitudinal guide member 19 being provided with a slot 22 registering with the slot 18 in the tongue. The evener 23 which is slidably supported on the tongue is provided with an eye 24 for the passage of the hammer bolt 25, which latter extends through and is guided in the slots 22, 18. A powerful helical spring 26 is supported on the tongue in rear of the evener, said spring being provided with terminal eyes 27 at its front and rear ends, the front eye 27 being engaged by the hammer bolt 25, while the rear eye 28 is securely connected with the tongue by means of a bolt 29. It will be seen that the longitudinal sliding movement of the evener is limited by the slots 22, 18, and that said evener is normally supported at the rearward limit of its movement by the contractile action of the spring 26. Pivoted in a slot 30 in the tongue in rear of the spring 26 is a lever A, the upwardly extending arm of which, 31, is connected with the hammer bolt 25 by means of a connecting rod 32 which is made of material sufficiently strong and rigid to prevent said rod from bending under the stress to which it will be subjected when the device is in operation. The relatively short downwardly extending arm 33 of the lever A is connected by a rod 34 with a relatively long arm or crank 35 extending downwardly from a rock shaft 36 which is fulcrumed in a suitable bearing on the cross bar 16. The reach bar 15 has a downwardly extending loop 35' through which the rod 34 is guided and which protects the said rod from interference with the hound frame when the vehicle is turned. It will also be seen that the connecting rod 34 is of such length as to permit the running gear to be lengthened or shortened, as may be required. The rock shaft 36 has a second relatively short downwardly extending arm 37 which is connected by a link rod 38 with a crank arm 39 extending upwardly from a rock shaft 40 supported on the rear anxle, and said rock shaft is provided with relatively short downwardly ex-

tending crank arms 41 that are connected by rods 42 with the brake bar 43 which is suspended from the cross bar 16 by means of links 44, said brake bar being equipped with 5 brake shoes 45 adapted to engage the hind wheels 46 of the vehicle.

A housing 47 is provided within which the spring 26 is accommodated. Hingedly mounted on the longitudinally slotted guide 10 member 19 of the frame is a latch member 48, which when the evener is moved forwardly so as to place the spring 26 partly under tension, may be positioned in rear of the hammer bolt to prevent rearward movement of the latter, thereby sustaining the 15 brake in released condition and enabling the vehicle to be backed in the customary manner.

As will be seen from the foregoing description, taken in connection with the drawings hereto annexed, the construction of the improved device is such that the brake is normally set by the action of the spring 26 and the intermediate means for transmitting power from the spring to the brake bar. When the vehicle is to be moved, and draft is applied to the evener, the whiffletree moves forwardly, and the hammer bolt through its connections will expand the 30 spring and release the brake shoes from engagement with the wheels. When the draft, or movement in a forward direction, of the evener ceases, the brakes will be automatically set by the action of the spring. It will 35 thus be impossible for the vehicle to crowd the team in going down hill, and undue strain upon the team, as well as dangerous accidents, will thus be avoided. The rock shaft 40 may be provided with an upwardly 40 extending hand lever 50 whereby the brake may be manually operated, either directly or through intermediate connections of a conventional character.

Having thus described the invention, what 45 is claimed as new, is:—

1. A running gear including a reach bar, a tongue, and a cross bar supported on the

reach bar, said tongue having longitudinal slots, a frame including a slotted guide bar supported on the tongue, a hammer bolt extending through registering slots in the frame bar and the tongue, an evener connected with the hammer bolt and guided on the tongue beneath the frame bar, a spring secured at one end on the tongue and having 55 its other end connected with the hammer bolt, a lever pivoted on the tongue in rear of the spring, a rod connecting the upwardly extending relatively long arm of said lever with the hammer bolt, a brake bar, links 60 connected with the cross bar on the reach bar and supporting the brake bar, and means for transmitting motion between the brake bar and the downwardly extending relatively short arm of the lever pivoted on the 65 tongue, said means including cranks and connecting rods whereby a relatively limited movement on the part of the brake bar shall require a relatively extensive movement on the part of the evener. 70

2. In a device of the class described, a tongue having a longitudinal slot, a frame including a slotted guide bar having supporting legs mounted on the tongue, means for securing said frame in position, an 75 evener guided between the tongue and the guide bar and having an eye, a hammer bolt engaging said eye and guided through registering slots in the tongue and the guide bar, a spring having one end secured on the 80 tongue and the other end connected with the hammer bolt to normally move the evener in a rearward direction, and a latch member pivoted on the frame and adapted to be positioned in rear of the hammer bolt when the 85 evener is moved forwardly against the tension of the spring to prevent the evener being retracted by the spring.

In testimony whereof I affix my signature in presence of two witnesses.

ROWLAND H. MAXFIELD.
